(57) CLAIM

The ornamental design for a bag, as shown and described.

DESCRIPTION

FIG. 1 is a top, front, left perspective view of a bag showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The evenly-dashed broken lines on the shaded and claimed surface of the handle represent a surface pattern that forms no part of the claimed design. The evenly-dashed broken lines surrounding unshaded surfaces depict portions of the article that form no part of the claimed design. The dotted broken lines in the drawings represent stitching which forms no part of the claimed design.
